(57) **CLAIM**

We claim the ornamental design for a shelving and storage unit with screen, as shown and described.

DESCRIPTION

FIG. 1 is a top front perspective view of a first embodiment of a shelving and storage unit with screen;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof;

FIG. 7 is a right side elevation view thereof;

FIG. 8 is a bottom front perspective view thereof;

FIG. 9 is a top rear perspective view thereof;

FIG. 10 is a top front perspective view of a second embodiment of a shelving and storage unit with screen;

FIG. 11 is a top plan view thereof;

FIG. 12 is a bottom plan view thereof;

FIG. 13 is a rear elevation view thereof;

FIG. 14 is a front elevation view thereof;

FIG. 15 is a left side elevation view thereof;

FIG. 16 is a right side elevation view thereof;

FIG. 17 is a bottom front perspective view thereof; and,

FIG. 18 is a top rear perspective view thereof.

Uniform broken lines illustrate portions of the shelving and storage unit with screen embodiments that form no part of the claimed design.

1 Claim, 14 Drawing Sheets
